(57) **CLAIM**

The ornamental design for a menu holder, as shown and described.

DESCRIPTION

FIG. 1 is a three-quarter rear perspective view of a menu holder showing my new design with a translucent front panel; FIG. 2 is a three-quarter front perspective view of the menu holder shown in FIG. 1;

FIG. 3 is a left side view of the menu holder shown in FIG. 1; FIG. 4 is a front view of the menu holder shown in FIG. 1; FIG. 5 is a bottom view of the menu holder shown in FIG. 1, which, due to the symmetry of my new design, is the same as the top view;

FIG. 6 is a right side view of the menu holder shown in FIG. 1;

FIG. 7 is a rear view of the menu holder shown in FIG. 1; FIG. 8 is a perspective view of the menu holder shown in FIG. 1 in an open position;

FIG. 9 is a three-quarter rear perspective view of a second embodiment of a menu holder showing my new design and having an opaque front panel;

FIG. 10 is a three-quarter front perspective view of the menu holder shown in FIG. 9;

FIG. 11 is a left side view of the menu holder shown in FIG. 9;

FIG. 12 is a front view of the menu holder shown in FIG. 9; FIG. 13 is a bottom view of the menu holder shown in FIG. 9, which, due to the symmetry of my new design, is the same as the top view;

FIG. 14 is a right side view of the menu holder shown in FIG. 9;

FIG. 15 is a rear view of the menu holder shown in FIG. 9; and,

FIG. 16 is a perspective view of the menu holder shown in FIG. 9 in an open position.
